US00D919256S

(12) **United States Design Patent** (10) **Patent No.:** **US D919,256 S**
(45) **Date of Patent:** **** May 18, 2021**

(54) **FOOTWEAR**

- (71) Applicant: **Crocs, Inc.**, Niwot, CO (US)
(72) Inventor: **Holly Thompson**, Loveland, CO (US)
(73) Assignee: **Crocs, Inc.**, Broomfield, CO (US)
(**) Term: **15 Years**
(21) Appl. No.: **29/699,918**
(22) Filed: **Jul. 30, 2019**
(51) LOC (13) Cl. **02-04**
(52) U.S. Cl. **D2/923**
(58) **Field of Classification Search**
USPC D2/896, 900, 916, 917, 923, 943,

(57) **CLAIM**

The ornamental design for footwear, as shown and described.

DESCRIPTION

FIG. 1 is a top perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The broken line showing of certain features is for illustrative purposes only and forms no part of the claimed design.

1 Claim, 7 Drawing Sheets
